**APPARATUS FOR THE DRYING OF SPAGHETTI
AND THE LIKE**Alfred Schrenk, Uzwil, Switzerland, assignor to Gebrue-
der Buehler, Uzwil, Switzerland, a Swiss firm

Application October 30, 1956, Serial No. 619,331

Claims priority, application Switzerland
November 12, 1955**1 Claim. (Cl. 34—1)**

It has been proposed before to dry spaghetti and other like food paste in long, solid or hollow, cordlike pieces with the aid of an electrical high-frequency field. In this drying process other sources of heat such as heat radiation or heat convection may also take part. The present invention relates to an improved electrode arrangement for high-frequency drying of spaghetti and like elongated looped food paste products, which is characterized in that a high-frequency electrode is formed as substantially horizontal plate.

A preferred embodiment of the invention is schematically illustrated in the accompanying drawing, in which the single figure depicts a drier with a horizontal plate electrode.

Referring now in greater detail to the drawing, the lead 3 extends from a high-frequency generator 1 to an electrode 5 which is formed as substantially horizontal plate. Above the latter are disposed metallic rods 6a which through the system of leads 2 are electrically connected to the generator 1. The electrode formed by the rods 6a is earthed, as indicated at 8. The spaghetti 7 to 35 be dried are suspended from the rods 6a.

2

The electrode 5 of course, need not be formed as a truly horizontal plane plate. Under certain circumstances it may hang slightly inclined in order to vary the spacing between the electrodes, or it may be formed 5 as a non-plane plate.

What I claim as new and desire to secure by Letters Patent is:

An apparatus for drying elongated looped food paste products comprising, in combination: a source of high frequency power; a substantially horizontal plate-like electrode connected with said source; and substantially horizontal support means disposed above and spaced from said electrode, said support means comprising a plurality of substantially parallel metallic rods for holding the looped products substantially perpendicularly to the plane of said electrode, each of said rods being connected to said source and constituting a second electrode with the looped products disposed between said second and said first mentioned electrodes.
